UNITED STATES PATENT OFFICE.

WILLARD H. FOX, OF NEW HAVEN, CONNECTICUT.

ENVELOP-OPENER.

SPECIFICATION forming part of Letters Patent No. 605,093, dated June 7, 1898.

Application filed February 21, 1896. Serial No. 580,224. (No model.)

To all whom it may concern:

Be it known that I, WILLARD H. FOX, a citizen of the United States, residing at New Haven, county of New Haven, and State of Connecticut, have invented a new and useful Improvement in Envelop-Openers, of which the following is a specification, reference being had to the accompanying drawings, forming part thereof.

10 My invention relates to that class of envelop-openers which perform their operation by cutting off one end of the envelop; and it has for its object to provide a device of this class which can be rapidly and easily operated and which will be provided with improved means for accurately predetermining the depth of the cut on the envelop and adjusting the cutters relatively to each other to compensate for wear.

15 To these ends my invention consists in the envelop-opener constructed and operating as hereinafter fully described, and particularly pointed out in the claims.

Referring to the drawings, in which like numerals designate like parts in the several views, Figure 1 is a plan view of a machine embodying the invention. Fig. 2 is an end view thereof. Fig. 3 is a plan view of the machine-frame with the cutters and their operating means removed, the same being drawn to a larger scale than in Figs. 1 and 2. Fig. 4 is a cross-section taken at line xx of Fig. 3. Fig. 5 is a rear elevation of the stationary cutter and its supporting-bar. Fig. 6 is an end view thereof. Fig. 7 is an end view of the guard. Fig. 8 is a front view of said guard. Fig. 9 is a front view of the movable cutter, its supporting-bar and operating-handle, and the adjustable gage for determining the depth 40 of the cut. Fig. 10 is an end view thereof.

The frame of the machine in its preferred form consists of two end pieces 1 1, intermediate cross-pieces 2 3, forming the bottom of the frame, the vertically-disposed cross-bar 4, erected upon said cross-piece 3, and the two slightly-inclined cross-bars 5 6, erected upon said cross-piece 2, (see Figs. 3 and 4,) all being cast integrally with each other. Said end pieces 1 1 are inclined downwardly 45 toward their front end and are provided at their inner side with the inclined flanges 7 to receive and support the table 8. (See Figs.

1 and 2.) The cross-piece 2 may be provided with the laterally-projecting ears 9, provided with holes to receive a screw to fasten the machine to a desk or table, if desired, and the cross-piece 3 is provided with the centrally-disposed projecting ear 10, having a tapped hole to receive the screw 12, (see Fig. 2,) which stays the lower end of the coil-spring 13, hereinafter referred to. The cross-bar 4 has the central slot or opening 14 extending throughout the greater portion of its length to lessen the weight of the machine.

The stationary knife 15 (see Figs. 5 and 6) is secured, by means of screws 16 or in any suitable manner, to its knife-bar 17, which knife-bar is adapted to be inserted between the inclined cross-bars 5 6 of the frame and is of slightly less thickness than the space 70 between said bars, whereby it is capable of a limited adjustment transversely of said space. Said knife-bar is provided at each end thereof with a conical socket 18, located at or near the bottom of its end walls, which 75 sockets receive the conical ends of two bearing-screws 19, passing through tapped holes in the end pieces 1 of the frame, check-nuts 20, applied to said screws at the outer side of said end pieces, (see Figs. 1 and 2,) serving 80 to hold them in any position of adjustment to compensate for wear between their conical ends and the sockets in the knife-bar. The knife-bar being thus supported, its slight movement for adjustment to compensate for 85 wear of its knife 15 is in the arc of a circle of which said screws constitute the center. To secure very accurate adjustment thereof, as well as to hold the bar securely in any position to which it may be moved, I utilize a series of adjusting-screws 21, passing through 90 tapped holes in the cross-bars 5 6 and bearing against the opposite sides of said bar, there being, as herein shown, three of such screws bearing against each of its sides. It will be 95 obvious that by retracting the screws 21 in one of said cross-bars and advancing those in the other bar a very delicate and accurate adjustment of the knife 15 can be secured in either direction.

The movable knife 22 is secured by screws 23 or in any suitable manner to the under side of a shoulder 24 on a knife-bar 25, (see Figs. 9 and 10,) which bar is provided at its

ends with conical sockets 26 to receive the conical ends of two bearing-screws 27, passing through tapped holes in the end pieces 1 of the frame, said screws carrying the check-nuts 28 at their outer ends. Provision is thus made for a rocking movement of said knife-bar about said screws as a center, and such movement in a forward direction is imparted to it through a forwardly-projecting handle-piece 29, located at the center thereof, said handle-piece having secured to its upper side the hand-rest 30, having a rounded upper surface and having fastened to its under side a buffer 31, of soft rubber or other similar material, which by being brought into contact with the table 8 limits the downward movement of said handle and serves as a cushion to deaden the force of the blow. Movement of said knife-bar in the opposite direction is secured by a closely-coiled spring 13, which, as before stated, is secured at its lower end to the cross-piece 3 by the screw 12 and at its upper end is suitably connected to said knife-bar or to a projecting lug 32 thereon (see Fig. 10) at the rear end of the handle-piece 29, said spring resting at its upper end against the curved outer edge of a wing 33, projecting from the knife-bar below said lug. By utilizing a closely-coiled spring, as described, which is expanded by the forward movement of the knife-bar, it not only returns said bar to its normal position when released, but serves as a stop to prevent further rearward movement of the bar. The shoulder 24 on said knife-bar 25 to which the movable knife is secured is inclined relatively to the axis of the bar, as shown in Fig. 9, whereby the knife 22 is caused to have a shear-cutting action against the edge of the stationary knife 15 when swung downwardly with said knife-bar, as is customary in this class of machines. A gage 34, having its upper edge correspondingly inclined and abutting against the under side of the knife 22, is secured to the lower side of the knife-bar by screws 35, passing through transverse slots in said gage, as shown in Fig. 10, whereby it is rendered adjustable transversely of the knife-bar. The front surface of said gage is made concentric with the axis of rotation of the knife-bar, as shown in Fig. 10, so that its gaging action upon the envelop held against said surface is the same at all points in the movement of the knife-bar, its function being to determine the depth of the cut by its position relative to the cutting edge of the knife 22.

A guard 36 is secured at its ends to the end pieces 1 of the frame by means of pins passing through holes in lugs 37 at the ends 60 of said guard, as shown, or in any convenient manner, said guard being located immediately in front of the stationary knife 15 and slightly above the table 8, with which it makes an acute angle, as shown in Fig. 2. The 65 main function of said guard is to prevent the fingers of the user of the machine from coming in contact with the knives and to serve

as a guide to facilitate the introduction of the envelop within the machine. I cause it to perform another function, however, by 70 locating at a convenient point therein the semicircular bend 38 and by providing the gage 34 with an opening 39 in alignment with said bend, (see Fig. 9,) whereby by introducing the pointed end of a cigar within said 75 bend and opening the machine is caused to serve as a cigar-cutter as well as a envelop-cutter.

The paper shavings removed from the end of the envelop by the cutters drop upon a 80 bottom piece 40 of the frame, which bottom piece is pivotally connected at one of its corners by a screw 41 to the under side of cross-piece 3, said cross-piece being slightly recessed to receive the same, whereby said bottom 85 piece is adapted to be swung outwardly to permit the shavings to be emptied into a waste-basket or other receptacle whenever a sufficient quantity thereof has accumulated to render such action necessary. I thus 90 avoid littering up the desk or table with such shavings.

In the use of the machine thus constructed the gage 34 is set in such position relative to the cutting edge of knife 22 as to limit the 95 depth of cut to a mere shaving, and knife 15 is adjusted by means of the screws 21 to a position in which its cutting edge occupies the proper relation to the plane of movement of the edge of knife 22 to secure a clean shear 100 cut. The envelop is then placed upon the table 8, as represented by dotted lines in Fig. 1, and moved rearwardly until its end abuts against the face of gage 34, and the disengaged hand is utilized to force the handle 29 downwardly until the buffer 31 strikes the table 8, thereby causing the knives to remove a thin shaving from the end of the envelop without danger of injury to the contents thereof. As soon as the handle is released the spring 13 returns it to its normal position, where it is ready for another blow. In this manner the operation of opening envelops can be performed very rapidly and easily.

The conical bearings for the two knife-bars, with their means for compensating for wear, insure a strict parallelism of the cutting edges of the knives at all times, and the means described for securing lateral adjustment of the stationary knife enables said cutting edges to be maintained in their proper relation to each other regardless of wear thereof.

By giving to the machine herein described 125 the combined functions of an envelop-cutter and a cigar-cutter I render it an exceedingly useful and convenient adjunct to the ordinary office equipment.

Having thus fully described my invention, 130 what I claim, and desire to secure by Letters Patent, is—

1. In an envelop-opener, the combination with a suitable frame, of the stationary knife

- 15 adjustably mounted upon said frame, knife-bar 25 pivotally mounted upon said frame and carrying the knife 22, said knife-bar being provided with the operating-handle 29 to the under side of which is secured the elastic buffer 31, the closely-coiled spring 13 for retracting said knife-bar, and table 8 mounted upon said frame in front of said knives, substantially as described.
- 5 2. The combination with the frame provided with the end pieces 11 and cross-bars 5 6, of the knife-bar 17 supported at its ends by the conical-pointed screws 19 passing through said end pieces and carrying the
- 10 knife 15, adjusting-screws 21 passing through said cross-bars 5 6 and bearing against oppo-

site sides of said knife-bar, and knife-bar 25 supported at its ends by the conical-pointed screws 27 and having knife 22 mounted thereon at an angle to its axis of movement, substantially as described.

15 3. The combination with the frame having mounted thereon the stationary cutter 15 and the rotary cutter 22, with means for operating the latter in opposite directions, of the bottom piece 40 pivotally secured to the under side of said frame, substantially as and for the purpose described.

WILLARD H. FOX.
